2,314,865

HEATING DEVICE

Rudolph A. Bierwirth, Haddon Heights, N. J., assignor to Radio Corporation of America, a corporation of Delaware

Application May 31, 1941, Serial No. 395,943

6 Claims. (Cl. 219—13)

This invention relates to heating devices, and more particularly to a device for heating conductive articles by induction from a source of energy of high frequency.

In many industrial applications, it is necessary, during the manufacture of various articles, to apply heat thereto. In some cases, it is necessary to apply the heat locally and with fair rapidity. One such example is in uniting sheets of metal or other material by means of rivets which are exploded with the aid of an explosive charge in order to effect an expansion of the rivet shank. According to the most common practice, a heating iron is brought into engagement with the head of the rivet in order to apply heat to the explosive charge. Among the disadvantages of such heating irons are that they must be maintained at a relatively high temperature, they require a relatively long period of time to bring them up to operating temperatures, they require replacement of heating irons for various articles which require treatment with different degrees of heat, so that a considerable period of time is necessarily lost while waiting for hot irons to cool and cold irons to come up to operating temperatures, and they have a short life.

The primary object of my present invention is to provide an improved heating device for industrial applications such as that noted above, which device will not be subject to the disadvantages of similar prior art devices.

More particularly, it is an object of my present invention to provide an improved heating device which is capable of applying heat locally in a small area.

A further object of my invention is to provide an improved heating device as aforesaid which is comparatively simple in construction and easy to handle.

In accordance with my invention, I provide a single turn coil which is frusto-conical in shape and couple the coil to a high frequency oscillator through a step-down transformer, the apex area of the coil being of small diameter (for example, of the order of the diameter of a rivet head). The oscillator may supply to the transformer about 300 to 1000 watts at frequencies in the neighborhood of from 300 kc. to 400 kc. A high current is induced in the secondary circuit, which includes the frusto-conical coupling coil, the latter setting up a highly concentrated magnetic field at its apex end so that, when it is brought into proximity with a metallic object, the latter will become heated by reason of the

eddy currents induced therein. The advantage of using a frusto-conically shaped coil is that a small spot may be heated in a flat surface while enough metal is provided to carry away the heat generated in the coil itself. If desired, a suitable air blast may be provided to assist in cooling the coupling coil.

The novel features that I consider characteristic of my invention are set forth with particularity in the appended claims. The invention, however, both as to its organization and method of operation, as well as additional objects and advantages thereof, will best be understood from the following description, when read in connection with the accompanying drawing, in which—

Fig. 1 is a view, partly in section, of a heating device formed according to my present invention and coupled to a suitable source of energy,

Fig. 2 is a sectional view taken on the line II—II of Fig. 1,

Fig. 3 is a top plan view of the frusto-conical coupling or heating coil,

Fig. 4 is a side elevation thereof, and

Fig. 5 is a top plan view of a modified form of coupling coil.

Referring more particularly to the drawing, wherein similar reference characters designate corresponding parts throughout, there is shown a tubular supporting member 1 of insulating material on which is wound the primary winding 3 of a transformer coupled to a suitable high frequency oscillator 5 by a concentric cable 7. Surrounding the primary winding 3 and spaced therefrom by a plurality of circumferentially distributed, longitudinally disposed, insulated spacing members 9 is the secondary winding 11 of the transformer. The primary winding 3 may consist of 56 turns of No. 14 wire wound in a single layer on the supporting tube 1, and the

secondary winding 11 may be made of a copper sheet about one-eighth inch thick and about four inches long, being formed into a tube which surrounds and is concentric with the primary winding 3, as clearly shown in Figs. 1 and 2. The longitudinally extending terminals 11a of the secondary winding 11 are, of course, in slightly spaced relation, and secured to the terminals 11a, as by rivets, solder, screws, or the like, are the terminals 13a of a single turn, frusto-conical coupling coil 13 having a small diameter at its apex end 13b, the axis of the coil 13 being angularly related to the axis of the concentric windings 3 and 11. As clearly seen from Fig. 1, the coupling coil 13, which may also be made from a strip of sheet copper, is so disposed relative to

the secondary winding 11 that its apex end 13b is most remote from the axis of the coils 3 and 11, whereby the apex end 13b is disposed in advance of the tubular winding 11 and nearest to the article to be heated.

When the system is set up for operation, the oscillator 5 supplies energy to the primary winding 3 whereby a high current is induced in the secondary winding 11 and the coupling coil 13 connected thereto. Since the coil 13 is of small diameter, particularly at its apex and 13b adjacent to which most of the current flowing in the coil 13 is concentrated, there is set up at the apex end of the coil 13 a highly concentrated magnetic field. If, now, the coil 13 is brought into proximity with the head of a rivet 15 which is intended to unite a pair of sheets 17 and 19, the rivet 15 will become heated because of the eddy currents induced therein by the aforementioned highly concentrated magnetic field. These eddy currents will be sufficient to explode a charge of explosive which has previously been placed in the hollow shank of the rivet 15 to thereby cause the rivet shank to expand slightly, as shown at 15a in Fig. 1, thereby firmly uniting the sheets 17 and 19. The comparatively large area of the coil 13 in relation to the relatively small area thereof adjacent to its apex end 13b where most of the current therein is concentrated permits the heat generated therein to be conducted away fairly rapidly. However, if desired, an air blast produced by a blower 21 may be fed through a tube 23 into the supporting tube 1, down to the coupling coil 13, as shown by the solid arrows in Fig. 1, to help cool the coil 13, and also back around the tube 1 into the space 25 between the primary winding 3 and the secondary winding 11, as shown by the dotted arrows, whereby to cool the winding 3 as well.

From the foregoing description, it will be apparent to those skilled in the art that I have provided an improved heating device which is capable of being energized by a high frequency source and which is capable of applying heat locally and with great efficiency to an article to be heated. Since the device is very light in weight and does not itself become appreciably hot, it is easy to handle even over extended periods.

Although I have shown and described but one embodiment of my invention, it will be apparent to those skilled in the art that many changes in the particular modification described, as well as other modifications, are possible. For example, instead of making the coupling coil frusto-conical in shape, it may be made of any other suitable shape and with its two ends either of the same or different diameters, as may be found most desirable. Also, instead of disposing the coil 13 with its axis as shown in Fig. 1, it may be arranged so that its axis is otherwise related to the axis of the coils. Thus, in another form of heating unit, I have arranged the coil 13 so that it extends forwardly of the secondary winding 11 with its larger base substantially in alignment with the forward end of the winding 11 and its apex end in front of this winding, the axis of the coil 13 being at an acute angle with the axis of

the windings 3 and 11. It is also possible, if desired, to form one or more radial slits 13c in the coil 13 extending from the larger diameter thereof in toward its apex end, as shown in Fig. 5, for example, whereby to further insure concentration of the high current flowing therein almost entirely around its apex end. Moreover, if desired, a suitable shield may be placed adjacent the terminals 11a of the winding 11, which will increase the efficiency of the unit. These and many other changes of a similar nature which will undoubtedly readily suggest themselves to those skilled in the art are possible within the scope of my invention. I therefore desire that my invention shall not be limited except insofar as it is made necessary by the prior art and by the spirit of the appended claims.

I claim as my invention:

1. An electrical heating device comprising a transformer having primary and secondary windings arranged on a common axis, said primary winding being adapted to be connected to a source of electrical energy, and a frusto-conical coupling coil connected to the terminals of said secondary winding, the axis of said coupling coil being angularly related to the axis of said windings.
2. An electrical heating device comprising an insulated tubular supporting member, a winding thereon constituting the primary winding of a transformer adapted to be connected to a source of electrical energy, a single turn, tubular, conductive member surrounding said primary winding, said member constituting the secondary winding of said transformer, and a single turn coupling coil having terminals connected to the terminals of said secondary winding, said coil being frusto-conical in shape whereby the current which may flow therein will be concentrated mostly in a region adjacent to its apex end, and the axis of said coupling coil being angularly related to the axis of said windings.
3. A heating unit according to claim 2 characterized in that the apex end of said coupling coil is most remote from the axis of said windings.
4. An inductor coil comprising a frusto-conical member having terminals for connection to a source of electrical energy, said member being provided with a plurality of slits extending from the larger end thereof toward its apex end whereby most of the current which may flow therein will be concentrated in an area in the vicinity of the apex end thereof.
5. An inductor heating coil comprising a frusto-conical member having terminals for connection to a source of electrical energy, said member being provided with a plurality of slits extending from the larger end thereof toward its apex and whereby most of the current which may flow therein will be concentrated in an area in the vicinity of the apex end thereof, and said member having an area which is large compared with said first named area whereby the heat generated therein by said current will be readily dissipated.
6. An inductor coil according to claim 5 characterized in that said slits are arranged radially on said coil.

RUDOLPH A. BIERWIRTH.
